(57) **CLAIM**

The ornamental design for a treadmill, as shown and described.

DESCRIPTION

FIG. 1 is a front, top perspective view of a treadmill, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged view of the area labeled 9 in FIG. 1; FIG. 10 is an enlarged view of the area labeled 10 in FIG. 1;

FIG. 11 is an enlarged view of the area labeled 11 in FIG. 1; FIG. 12 is an enlarged view of the area labeled 12 in FIG. 1;

FIG. 13 is an enlarged view of the area labeled 13 in FIG. 2;

FIG. 14 is an enlarged view of the area labeled 14 in FIG. 2;

FIG. 15 is an enlarged view of the area labeled 15 in FIG. 3;

FIG. 16 is an enlarged view of the area labeled 16 in FIG. 7;

FIG. 17 is an enlarged view of the area labeled 17 in FIG. 7; and,

FIG. 18 is an enlarged view of the area labeled 18 in FIG. 8.

The dot-dash broken lines of the treadmill in FIG. 1 illustrate a boundary and cut line of the enlarged view in FIG. 9 and form no part of the claimed design.

The dot-dash broken lines of the treadmill in FIG. 1 illustrate a boundary and cut line of the enlarged view in FIG. 10 and form no part of the claimed design.

The dot-dash broken lines of the treadmill in FIG. 1 illustrate a boundary and cut line of the enlarged view in FIG. 11 and form no part of the claimed design.

The dot-dash broken lines of the treadmill in FIG. 1 illustrate a boundary and cut line of the enlarged view in FIG. 12 and form no part of the claimed design.

The dot-dash broken lines of the treadmill in FIG. 2 illustrate a boundary and cut line of the enlarged view in FIG. 13 and form no part of the claimed design.

The dot-dash broken lines of the treadmill in FIG. 2 illustrate a boundary and cut line of the enlarged view in FIG. 14 and form no part of the claimed design.

The dot-dash broken lines of the treadmill in FIG. 3 illustrate a boundary and cut line of the enlarged view in FIG. 15 and form no part of the claimed design.

The dot-dash broken lines of the treadmill in FIG. 7 illustrate a boundary and cut line of the enlarged view in FIG. 16 and form no part of the claimed design.

(Continued)

The dot-dash broken lines of the treadmill in FIG. 7 illustrate a boundary and cut line of the enlarged view in FIG. 17 and form no part of the claimed design.

The dot-dash broken lines of the treadmill in FIG. 8 illustrate a boundary and cut line of the enlarged view in FIG. 18 and form no part of the claimed design.
